AUXILIARY HEATER FOR STEAM BOILERS

George Morris Conekin, Philadelphia, Pa.

Application August 25, 1931. Serial No. 559,334

2 Claims. (Cl. 237—67)

The invention relates to a steam heating system having pipe lines of substantially unequal lengths and to each of which radiators corresponding thereto are attached and supplied with steam therefrom, and an object of the invention is to provide and connect an auxiliary heater in such a system so as to insure a proper heating through the medium of the longer line of the pipe lines thereof even under severe operating conditions to 10 which such a heating system must at times respond.

In steam heating systems having the usual steam boiler and furnace therefor and wherein there are a considerable number of radiators which are connected to a relatively long supply pipe line or section for receiving steam from the boiler and wherein there are a lesser number of radiators connected to a relatively short supply pipe line or section for receiving steam from the boiler experience has developed the fact that 15 frequently the heating effect of radiators supplied through the long pipe line—and particularly of the radiators more remote from the boiler as for example the radiators in the upper part of a building—is relatively small or deficient due to 20 insufficiency in the supply of steam thereto and an object of the present invention is to employ an auxiliary heater and to incorporate it in the heating system in such a manner that it is functionally associated with the water and steam section of the boiler, with the furnace for the boiler, and with the long supply pipe line or section so 25 that the steam supply to the long pipe line will be augmented and insured whereby the heating 30 effect of each of the several radiators connected to the long supply pipe line or section will favorably compare with the heating effect of each of the radiators connected to the short supply pipe line or section.

A further object of the invention is to provide 35 an auxiliary heater of this character adapted to utilize the heat of the smoke and hot gases and other products of combustion which pass off to the chimney or flue and the heat of which is usually 40 lost after such products of combustion leave the steam boiler of the heating system.

A further object of the present invention is to 45 provide an auxiliary heater adapted to permit steam to enter the line to be reinforced and at the same time permit any water of condensation 50 to drain back into the steam boiler.

With these and other objects in view, the invention consists in the construction and novel combination and arrangement of parts herein- 55 after described, illustrated in the accompanying drawings, and set forth in the claims hereto appended, it being understood that various changes in the form, proportion, and minor details of construction, within the scope of the claims, may 60 be resorted to without departing from the spirit of

the invention or sacrificing any of the advantages thereof.

In the drawings:

Figure 1 is a side elevation of an auxiliary heater constructed in accordance with this invention and shown applied to a steam heating system.

Fig. 2 is a vertical sectional view taken substantially on the line 2—2 of Fig. 1, the steam boiler being shown in elevation.

Fig. 3 is a diagrammatic view illustrating the hook up of the several members or parts of a steam heating system realizing the invention. In this figure, the casing construction for the auxiliary heater thereof is shown with a portion 70 of the casing construction removed whereby the auxiliary heater or auxiliary heater element appears in full lines. For the purpose of better illustrating the invention the parts in this figure are shown in the same hook up as in the other figures but in this Fig. 3 the parts occupy a somewhat different physical position relative to each other from that shown in the other figures.

In the accompanying drawings, in which is illustrated the preferred embodiment of the invention, 1 designates a steam boiler and furnace construction provided at the top with riser pipes 2 and 3 leading from the usual steam and water space of the boiler and with a smoke pipe or flue extending from the furnace section of the boiler and furnace construction to the chimney provided therefor. The smoke pipe or flue comprises as a part thereof a drum or casing 5 wherein there is encased an auxiliary heater, or auxiliary heating element or section, 6. The auxiliary heater 6 is of radiator formation, and while one section or unit is illustrated in the accompanying drawings, the auxiliary heater may comprise any number of such sections, as will be readily understood. The pipe connections of the smoke pipe may connect the drum or casing 5 with the steam boiler 1 and with the chimney or flue, so that when the smoke, hot gases and other products of combustion, which usually pass from the steam boiler through the chimney or flue, pass into the smoke pipe, they are forced to pass through the drum or casing 5 and impinge against the auxiliary heater. Owing to the auxiliary heater being of radiator formation, the smoke and other products of combustion pass through and around the auxiliary heater, so that the latter is entirely subjected to the action of the heat of the smoke and other products of combustion.

The riser pipes 2 and 3 are respectively connected with long and short lines 7 and 8 which extend to and deliver the steam from the steam boiler to the radiators, not shown. In practice, in steam heating systems for domestic use, the long line 7 will be found relatively weak with 115 120

reference to the efficiency of the other short line, 8. The long and short lines 7 and 8 are shown in the accompanying drawings as extending substantially horizontally from the riser pipes 2 and 3—but as is well recognized in practice these should slightly incline downwardly towards the riser pipes 2 and 3 to permit drainage back towards the riser pipes 2 and 3—and said lines 7 and 8 are connected with drain pipes 9 and 10, which conduct any water of condensation in the lines 7 and 8 back to the steam boiler to prevent such water of condensation from interfering with the passage of the steam through the lines. The drain pipes 9 and 10 are vertical and the auxiliary heater 6 is connected at the top at one end by a pipe 11 with the drain pipe, by a T coupling 11^a at a point above the water line of the steam boiler 1. The pipe 11 is preferably located above the top of the steam boiler, and it is preferably provided with a thermometer 12. Steam from the auxiliary heater will pass out from the top of the heater through the pipe 11 to the upper portion of the drain pipe 9, and will then pass upwardly through the drain pipe and enter the relatively long line 7 and increase the heating efficiency of the same. By means of the auxiliary heater steam of a relatively high temperature is introduced into the pipe line 7 to supplement the steam which passes directly from the boiler into the line through the riser 2.

The auxiliary heater is supplied with water by the return pipe 13 from the radiators, and the water of condensation from the radiators thus supplied to the auxiliary heater is then heated, and that portion thereof which is converted into steam and delivered to the pipe line 7 flows from the auxiliary heater through the pipe 11 and down the drain pipe 9 to the lower portion of the steam boiler, viz., to the water space of the steam boiler, and is delivered to the latter in a heated condition, thereby increasing the efficiency of the steam boiler by introducing preheated water into the same instead of water at a relatively low temperature, as is the case where the return pipe is connected directly with the steam boiler and the water of condensation not preheated before being delivered to the steam boiler.

50 The return pipe extends to a point below one end of the auxiliary heater and is connected with the same by a vertical pipe 14 at the lower corner of the auxiliary heater at a point diagonally opposite the outlet 15 with which the pipe 11 is connected. The auxiliary heater is provided at the other end with a cap 16 for closing the outlet 17 when the latter is not employed. The return pipe 14 and the discharge pipe 11 are connected with the auxiliary radiator by suitable couplings, 60 and the said auxiliary heater is supported by spaced vertical standards 18 and 19 which are provided at their lower ends with flanged caps 20 and 21 suitably secured to the floor or other support upon which the steam boiler is mounted. 65 The vertical standards 18 and 19 preferably consist of pipes which are suitably plugged. The standard 18 is relatively short and is coupled to the lower end of the vertical return pipe 14 at the point where the same is connected with the radiator return pipe 13. The standard 19 is suitably coupled at the other side of the auxiliary heater opposite to the point where the return pipe 14 is connected, and the spaced vertical supports provide a strong, durable structure for the 70 auxiliary heater. The auxiliary heater is prefer-

ably arranged close to the steam boiler, as clearly illustrated in Fig. 1 of the drawings, to subject it to the intense heat of the products of combustion passing from the steam boiler to the chimney or flue, but this auxiliary heater does not affect the construction of the boiler, being arranged in the smoke pipe thereof. The short pipe connection extending from the casing or drum 5 may be provided not only at the upper but at the lower portion thereof, and the relatively long pipe line extending from the riser 2 is preferably connected to the said drum so as to thoroughly subject it to the heat of the products of combustion passing through the smoke pipe.

What is claimed is:

1. In a steam heating system, in combination, a steam boiler having riser pipes extending upwardly from the top thereof, a long pipe line having a substantially horizontal section connected to one of the riser pipes, a short pipe line having a substantially horizontal section connected to another of the riser pipes, radiators, some of which radiators are connected to and supplied with steam from the long pipe line and others of which radiators are connected to and supplied with steam from the short pipe line, vertical drain pipes, there being a drain pipe for and corresponding to each of said pipe lines, each of said drain pipes being arranged adjacent the steam boiler and extending from a horizontal section of the pipe line to which it corresponds to the lower portion of the boiler for delivering waters of condensation draining therethrough back into the water-containing section of the boiler, a smoke conduit extending from the combustion space of the steam boiler, a drum or casing provided in or by said smoke conduit, an auxiliary heater arranged within the drum or casing in the path of the smoke and other products of combustion passing through the smoke conduit, a discharge pipe leading from the upper or steam delivery portion of the auxiliary heater and extending to and communicating with the drain pipe of the relatively long pipe line, said discharge pipe being connected to said last mentioned drain pipe at a point which is above the water line of the boiler, and a radiator return pipe for connecting the several radiators to the auxiliary heater at the lower portion or water intake end thereof.

2. A steam heating system as defined in and by the preceding claim, wherein the return pipe for the radiators is connected to the auxiliary heater through the medium of a vertical pipe located below the auxiliary heater so as to deliver return water upwardly into the bottom portion of the heater and at a point directly opposite the place where the steam and any water leaving the auxiliary heater pass upwardly therefrom through the discharge pipe that is connected to the drain pipe connecting the long pipe line and the lower portion of the boiler and wherein the auxiliary heater is supported on vertical standards, one of which standards serves as said vertical pipe leading into the auxiliary heater.

GEORGE MORRIS CONEKIN.
